(57) **CLAIM**

The ornamental design for a hand worn pillow as shown and described.

DESCRIPTION

FIG. 1 is an isometric view of a hand worn pillow showing my new design;

FIG. 2 is a front elevational view thereof;

FIG. 3 is a rear elevational view thereof;

FIG. 4 is a right elevational view thereof;

FIG. 5 is a left side elevational view thereof;

FIG. 6 is a top plan view thereof;

FIG. 7 is a bottom plan view thereof; and,

FIG. 8 is a perspective view of the hand worn pillow shown in a configuration of use with environment thereof, showing my new design.

The broken lines depict environment and form no part of the claimed design.

1 Claim, 5 Drawing Sheets
